AUTOMATON MERCHANTISING DEVICE

Frank L. Dale, New York, N. Y., assignor to Mechanical Man, Inc., New York, N. Y., a corporation of New York

Application December 17, 1938, Serial No. 246,322

8 Claims. (Cl. 46—9)

My invention has to do with an automaton merchandising device, similar, in a generic sense, to the invention set forth in the patent granted to me, No. 2,105,904, January 18, 1938. In said patent the set-up includes a body, an oscillatable head, and an arm, the head and arm being mechanized in such fashion that as the head is moved to a profile posture, the arm concurrently is raised to salute while additional elements function to simulate the act of smoking.

With the present invention, I have enhanced the merchandising appeal of the robot by incorporating means for causing the figure to bow, conjunctively with the act of salutation, and to actuate one arm thereof to point to the article on display as the head is turned in profile in the direction of the merchandise. I have also worked out certain refinements in the mechanical smoking apparatus.

In order to give an understanding of the invention, I have illustrated in the drawings a selected embodiment thereof, which will now be described, and after which the novel features will be pointed out in the claims.

In said drawings:

Fig. 1 is a front elevation of the body of the figure, the major portion thereof being shown in vertical section.

Fig. 2 is a partial transverse section taken along lines 2—2 of Fig. 1.

Fig. 3 is a side view corresponding to Fig. 1, showing the body in bowed position.

Fig. 4 is a detail elevation of the air-pump.

Fig. 5 is a similar view of the disc which operates with the upper extremity of the pump.

Fig. 6 is a front elevation of the complete figure with the left arm in pointing position, and

Fig. 7 is a side elevation of the figure illustrating the body bowed and the right hand at salute.

Generally, the figure comprises a body 10, head 11, arms 12 and 13, and legs 14 and 15.

A pertinent fact with regard to the arms is that the forearms are disposed at an angle to the upper arms—this feature being of especial importance with regard to pointing, as will be subsequently explained.

The body is shown as cylindrical, with a top 16 and bottom 17, although it may be of any desired configuration suitable for enclosing the operating mechanism. Disposed within the body towards the base thereof, and with its axis arranged vertically, is a motor 18. A strut 19 extending transversely between the uprights 20 and 21, serves as a bed for the motor, and

the worm shaft 22 of the motor meshes with the worm-gear 23, carried by shaft 24 mounted in bearings 25 of uprights 20 and 21. Companion shaft 26 is disposed above shaft 24 in bearings 27. Suitable reduction gearing comprising a small pinion 28 on shaft 26 and a larger pinion 29 on shaft 26 is devised to rotate shaft 26 at a speed appropriate to the diverse mechanical movements now to be described.

Concerning firstly the bow, base 17 of the body 10 is connected by a hinge, as 30, to the top section of each leg 14 and 15. Engaging the respective hinges at 31 are the lower terminals of vertical rods or pitmans 32, 32', the opposite terminal of rod 32 being connected to the lower end 33 of link 34 carried by shaft 35, while the opposite terminal of rod 32' is attached to the lower end 33' of crank arm 34', which latter is also mounted on shaft 35. The other end 36 of the crank-arm 34 has pivoted thereto a comparatively short rod 36' which parallels rod 32 and is similarly connected at the opposite terminal to a crank 37 fixedly carried by the adjacent end of shaft 26. When motor 18 is energized, the body will be constrained forwardly on hinges 30 through the medium of the connections just described. In other words, the body will be tilted with respect to legs 14 and 15, in simulation of a bow, as illustrated in Figs. 3 and 7 of the drawings.

Next in order are the arm movements. Although their gesticulations are different, both arms 12 and 13 are actuated by shaft 26. Right arm 12 is connected to the shaft by an angular extension 38 and is adapted to be moved from a position of repose—see Fig. 6—to one of salute—see Fig. 7. Left arm 13, upon the other hand, is designed to oscillate laterally to simulate the act of pointing—and this is accomplished by pivoting the lower terminal of rod 39 to the crank-arm 40 of shaft 26, then connecting the opposite terminal of the rod to one arm 41 of a bell-crank 42, interposing another link 43 between arm 44 of the bell-crank and crank-arm 45, and still another link 46 between crank-arm 45 and stub shaft 47, which latter is positioned in housing 48 and carries the upper part of the arm 13—note particularly Figs. 1 and 2. Also in this connection, it will be observed that crank-arm 45 is rigidly mounted on a relatively short vertically extending shaft 49, the base of which and shaft 35, are freely movable in the T coupling 50. A collar 51 encircling shaft 35 at each end of coupling 50 and held by a set-screw 55

51", serves to preclude lateral movement of the coupling.

The smoking apparatus, as exhibited in Figs. 1, 4 and 5, comprises in part a cylinder 51, a piston 52 and a piston-rod 53 connected to crank-arm 40. At the upper extremity of the cylinder is a right-angular extension 54 having an elongated aperture 55 and pivoted to upright 21 at 56. Upright 21 is provided with two openings 57 and 58, conveniently connected to the mouth and nose of head 11 by means of flexible tubings 59 and 60. As the piston is reciprocated, the cylinder 51 swings to and fro on its pivot 56, alternately causing openings 57 and 58 to register and unregister with respect to aperture 55, and working in synchronism with the movement of the piston, produces a draft on the cigarette 61 and an exhalation of smoke through the nostrils of 61'. This construction and arrangement of parts embodies a capital advantage over the ball valve contraption described in my patent because it is devoid of any elements which will become clogged with tobacco tar.

Depending from head 11 is a neck portion 62 with a flanged base 63, rotatably mounted beneath an annular collar 64. To complete the assembly, the outer end of shaft 49 is equipped with a spider 65 permanently fastened to the inner wall of the neck. Oscillation of the head unit is effected through crank-arm 40 and links 39 and 43.

Normally the robot assumes a position similar to that illustrated in Fig. 6, the body 10 erect, the head 11 facing left, the right arm 12 at rest and the left arm 13 pointing or at least being removed outwardly from the body. Upon starting motor 18, the body begins to tilt forwardly, the right arm commences to raise and the left arm oscillates towards the body—these motions being continued until the respective elements reach the limit of their travel and the gestures are complete—with the body bowed, the right arm at salute or adjacent the head, and the left arm disposed towards the front of the body, as shown by dotted lines. Then the body, head and arms return to normal postures, and the cycle begins over again.

The smoking mechanism may be timed to operate during the oscillation of the head, at the limits of its oscillation, or only when the head is facing front.

If desired, a loud speaker may be installed within the body of the figure and operated from a remote point. And other features may be incorporated which will lend additional animation to the invention.

While I have illustrated and described with particularity only a single preferred form of my invention, I do not desire to be limited to the exact structural details thus illustrated and described, but intend to cover all forms and arrangements which come within the scope of the following claims. For example, the principles involves in the raising of the right hand to the head and the swinging of the left arm from the body while simulating the gestures of saluting

and pointing, may be employed in connection with other mechanical movements not herein specifically described.

I claim:

1. A figure including a body, a head, a pair of arms pivoted to the shoulders of the body and normally depending therefrom, and motor-actuated means for elevating one arm and then moving the same so that the lower portion thereof is proximate the head and for turning the other arm away from the body. 5

2. A figure including a body, a head, an arm pivoted to one shoulder and oscillatable on a vertical axis, and motor-actuated means for operating said arm. 10

3. A figure including a body, an oscillatable head normally disposed at profile, an arm pivoted to one shoulder and oscillatable on a vertical axis to normally occupy a position removed from the body, and motor actuated means for turning 20 the head to front dress and moving said arm towards the body.

4. A figure including a body, a head oscillatable in a horizontal plane, an arm pivoted to one shoulder of the body and oscillatable in a plane 25 parallel with said head, and motor-actuated means designed to turn the head and the arm.

5. A figure including a body, a head oscillatable in a horizontal plane, an arm pivoted to one shoulder of the body and oscillatable on a vertical axis, and motor-actuated means designed to turn the head from front dress to profile and the arm from a position in front of the body to a pointing position removed from the body, and vice versa. 30

6. A figure including in combination, a body, a head, an oscillatable arm, and a pair of legs, the body being hingedly connected to the legs, and motor-actuated means for causing said body to bow and said arm to be raised proximate the 40 head.

7. A figure including in combination, a body, an oscillatable head, an arm pivoted to one shoulder and oscillatable on a vertical pivot, and motor-actuated means for causing the head to move towards said shoulder as the arm is swung from a position forwardly of the body to a position outwardly with respect to the body. 45

8. A figure including a body and an oscillatable head, the mouth of the head having an opening 50 for a lighted cigarette or the like, an upright provided with an opening, a pump having a piston rod and being oscillatable about a fixed axis with respect to said upright and further having a pair of ports for alternate communication with 55 said opening, tubes connecting the opening of the mouth and the nostrils with said ports, whereby upon oscillation of the pump in one direction smoke is drawn into the pump and upon oscillation in the other direction smoke is expelled through 60 the nostrils, a motor, a shaft in geared relation to said motor, a crank-arm carried by said shaft, a pair of pitmans interposed between the crank-arm and the head, and said piston-rod being also connected to the crank-arm. 65

FRANK L. DALE.
